UNITED STATES PATENT OFFICE.

ROGER E. REED, OF DOUGLAS, MICHIGAN, ASSIGNOR OF TWO-THIRDS TO
ELMER E. WEED, D. MILTON GERBER, AND CORNELIUS GERBER, OF
SAME PLACE.

BASKET-MAKING MACHINE.

SPECIFICATION forming part of Letters Patent No. 601,778, dated April 5, 1898.

Application filed May 27, 1897. Serial No. 638,347. (No model.)

To all whom it may concern:

Be it known that I, ROGER E. REED, a citizen of the United States of America, residing at Douglas, in the county of Allegan and State 5 of Michigan, have invented certain new and useful Improvements in Basket-Making Machines; and I do hereby declare the following to be a full, clear, and exact description of the invention, such as will enable others skilled 10 in the art to which it appertains to make and use the same, reference being had to the accompanying drawings, and to letters of reference marked thereon, which form a part of this specification.

15 The invention relates to improvements in basket-making machines, and embodies means for the manufacture of splint baskets, which means include mechanism for gagging or centering the splints, bending them over a 20 form, applying and attaching the hoops by means of mechanically-driven staples, and in removing the completed basket from the form.

With the above ends in view my invention consists in a basket-making machine which 25 comprises a horizontally-supported basket-form, a cap or hood which is mounted on a line therewith, so as to be movable to and from the form, and a stapling-machine which is mounted so as to be moved to an operative 30 position over the form or swung away from the form when not in use, the driving mechanism of the stapling-machine being in gear with the shaft which carries the form.

The invention also consists in the combination, 35 with a basket-making machine, of instrumentalities organized for the manufacture of a splint basket, which comprise a suitably-driven horizontal shaft which carries a form, said form being circular in cross-section and tapered longitudinally, means for imparting to said shaft both an intermittent rotary and a continuous rotary movement, a bending and holding cap or hood mounted on a longitudinally-movable shaft which is connected with means for moving said shaft toward or away from the form upon which the splints are held by said cap, a stapling device mounted on a swinging support or standard, so that the staple-drivers thereof may be 45 brought into an operative position immediately above the longitudinal axis of the form

or moved rear of the form, together with mechanism for making connections and driving the assembled parts.

My invention also consists in a basket-making machine having a horizontal shaft upon which is mounted a basket-form and a shaft in line therewith which carries a cap or hood which is movable to and from the basket-form, so as to bend the splints and maintain 55 them in place upon the form while the staples are being driven by a stapling-machine which is in gear with the shaft which drives the basket-form.

My invention also consists in providing the 60 shafts which carry the basket-form and the cap or hood with spring-projected rods which engage with the splints, one of the rods serving to bend the splints into the concave end 65 of the form and the other to remove the basket when completed from the form.

My invention also consists in the combination, with a basket-form, of a stapling-machine which is mounted so as to be moved over the form or to the rear of the same, said 70 stapling-machine having means for connecting it with the driving-gear which rotates the shaft upon which the form is mounted, said stapling-machine being constructed to make and drive two staples simultaneously, 75 the form serving as an anvil for clinching the staples.

My invention also consists in the combination, with a basket-making machine, of a shaft having at one end a form, mechanism for imparting either a rotary or an intermittent rotary movement thereto, a second shaft having a bending and holding cap or hood, means for moving said second shaft toward and away from the shaft which carries the form, a stapling-machine mounted upon a pivotally-supported frame, and means for manually moving and holding the stapling-machine over the longitudinal axis of the form and mechanically driving the staples when so positioned, 90 said stapling-machine being so positioned upon its support that it will move automatically out of an operative position when pressure is removed from its supporting-frame, 95 as will be hereinafter set forth.

My invention also consists in the combination, with a basket-making machine, of a

swinging or pivoted support which carries a stapling-machine, a reciprocating shaft which is connected to a crank-shaft, the swinging support being mounted thereon, a lever for 5 moving the swinging support and stapling-machine carried thereby over the longitudinal axis of the shaft carrying the form, and mechanism for intermittently rotating the shaft which carries the form and reciprocating 10 the operating shaft or bar of the stapling-machine.

My invention also consists in providing the shaft upon which the form is mounted with 15 means for imparting thereto an intermittent rotary movement, a driving-pulley mounted on said shaft, and a clutch for engagement with the driving-pulley to impart a rotary movement to the form, the shaft also having a friction-brake to prevent rotation of the 20 parts unless positively driven, as will be hereinafter set forth.

My invention further consists in the combination, with a basket-making machine having a form which is mounted on a horizontal 25 shaft and means for imparting an intermittent rotary motion thereto, of a stapling-machine which is pivotally supported so as to be moved over the form or to one side of the same, the stapling-machine having mechanism 30 for making and driving two staples simultaneously, the base portion of the stapling-machine carrying hoop-guides which are positioned in line with the staple-drivers, as will be hereinafter set forth.

35 My invention also consists in combining, in a basket-making machine, a staple forming and driving mechanism which embodies mechanism which will drive the staples made thereby through the hoops of the basket so that 40 said staples will be positioned diagonally with the grain of the wood both of the hoops and splints.

My invention further consists in providing a staple making and driving machine with a 45 pair of frames, one fixed and the other movable, the movable frame being in gear with the shaft which carries the basket-form, each of the frames having on opposite sides of its center duplicate parts, so that each reciprocation of the shaft will form and drive two 50 staples, the basket-form serving as the anvil upon which the staples are clenched.

The invention further consists in providing the stapling-machine in advance of the staple making and driving mechanism with hoop-rollers, the stapling-machine also carrying in 55 advance of said rollers a cross-bar having upwardly-projecting pins, which act in conjunction with the rollers and serve as hoop-guides, 60 as will be hereinafter set forth.

The invention further consists in the construction, combination, and organization of the parts, as will be hereinafter fully set forth, and specifically pointed out in the claims.

65 In the accompanying drawings, which illustrate my invention, Figure 1 is a side elevation, the form of hood being shown separated

or in a position to receive the splints, the stapling-machine being positioned in rear of the form. Fig. 2 is a plan view, the stapling- 70 machine being in a vertical position or only partially over the form, the hood occupying the position that it would in bending and holding the splints upon the form. Fig. 3 is an end elevation looking toward the left-hand 75 side of the machine, the stapling mechanism being removed from its support. Fig. 3^a is a diagram view or side elevation showing parts of the fixed and movable frames of the stapling-machine which are carried by the swinging support. Fig. 4 is an end elevation looking 80 toward the right-hand side of the machine. Fig. 5 is a detail perspective view of the centering device for the splints and its support. Fig. 6 is a longitudinal sectional 85 view of the form and of the cap or hood. Fig. 7 is a side elevation, partly in section, the stapling mechanism being detached. Fig. 8 is a detail sectional view taken on the line 8 8 of Fig. 7. Fig. 9 is a vertical section taken 90 through one of the drive-pulleys to show the clutch mechanism. Fig. 10 is a sectional view taken on the line 10 10 of Fig. 9. Fig. 11 is a detail perspective view of the clamping- 95 band of the clutch detached. Fig. 12 is a front elevation of the staple making and driving mechanism, parts of the same being broken away in order to better illustrate the construction thereof. Fig. 13 is a sectional 100 view taken on the line 13 13 of Fig. 12. Fig. 14 is a side elevation of the staple making and driving mechanism. Fig. 15 is a detail 105 sectional view of the staple making and driving mechanism, taken on the line 15 15 of Fig. 14, the hoop rollers and guides being removed. Fig. 16 is a perspective view of one of the 110 staple formers and drivers detached. Fig. 17 is a front elevation of the staple-driver detached from the staple-former. Fig. 18 is a view of the trip which operates the staple- 115 bar to retract the same on the downward movement of the upper frame, and Fig. 19 is an end view of the lower end of the staple-former.

A refers to the base of the machine, preferably a casting having vertical and horizontal flanges and a series of upwardly-projecting portions or blocks, to which are bolted or otherwise secured standards or steeple-frames B, C, D, E, and F, as well as bearings a a' b b' c c', the bearings a a' carrying a crank-shaft P, the other bearings having journaled therein transverse rock-shafts H³ and L⁵, each of these rock-shafts having arms or members which project upwardly therefrom. 120 125

The steeple-frames are tied together by means of tubular bars G G, which are in sections, each section of said bars being placed between the frames, and through the tubular sections pass rods with threaded ends, nuts engaging therewith and with the outer frames. The frames B and D have bearings below the tie-rods G G for a shaft H, upon the outer end of which is mounted a pulley or brake- 130

wheel H^5 , over which may be placed a belt having a weight connected to one end, while the other end is secured to the floor or elsewhere, the function of the belt and weight being to prevent the rotation of the shaft H when said shaft is out of gear with its drive-pulley H' , said pulley being loosely mounted on its shaft, which has rigidly secured or keyed thereto a clutch of any suitable type, preferably as shown in Figs. 9, 10, and 11 of the drawings.

The clutch which I prefer to use embodies in its construction an encircling band h^4 , having lugs h^5 and h^6 attached adjacent to the ends of said band, the band being adapted to engage with the hub of the driving-pulley. The casing h of the clutch-section is rigidly attached to the shaft upon which the drive-pulley is mounted and has projecting portions into which the lugs extend, one of said extended portions having a set-screw for engagement with the lug h^5 to provide adjusting means for the band and the other lug has an aperture through which passes a finger or rock-arm h^7 , which is pivoted thereto and has a beveled end for engagement with the beveled end of the lug h^6 , so that when the outer end of the arm h^7 is raised against the combined action of a spring and the spring tendency of the band h^4 said band will embrace the hub-section of the driving-pulley, so as to connect the pulley with the shaft. Upon the shaft H is mounted a slide h' , the end nearest the clutch being conical for engagement with the rock-arm h^7 . The slide h' is operated by a foot-lever H^2 , carried by the end of a transverse rock-shaft H^3 , which shaft has an upwardly-projecting member, the upper end thereof being bifurcated and slotted for engagement with pins which project from a loose ring or band carried by the slide. The end of the foot-lever H^2 is held normally raised by a spring which extends therefrom and is connected to the standard D .

The shaft H has a pinion h^2 keyed thereon so as to be in mesh with a cog-wheel I , and one of the faces of said pinion serves as a stop for the slide h' to limit its movement in the direction that it is thrown by the spring. A depression of the foot-lever H^2 moves the slide to the left, so as to cause the hub of the driving-pulley to be engaged by the encircling band of the clutch, and causes the shaft and pulley to move in unison, and as soon as the clutch is removed from the foot-lever the slide will be disengaged from the clutch and movement of the shaft will be prevented by the friction on the brake-pulley H^5 .

The frame D is braced against lateral movement by straps or rods, which extend from points near the upper end of the same diagonally toward the base, to which the lower ends are attached.

The standard or frame C , which is of less height than the other standard or frame, is bolted or attached to the end standard B by means of tie-rods G' , and it has bearings $c^2 c^3$

for a vertical shaft I' , the lower end of which carries the gear-wheel I , while to its upper end is attached a disk I^2 or its equivalent, which may be a crank-arm. To the disk, by means of a wrist-pin, is secured a pitman I^3 , the same engaging with a sliding frame which is mounted upon the standards $B D$, said standards having plates $i^1 i^2$ bolted to the upper ends of the same, and these plates engage with bearings $i^2 i^3$ for a shaft K' , the shaft-bearings being connected to each other by strips or bars $k k'$. The bearings are provided with recesses which engage the plates or strips $i^1 i^2$, so that the bearings may have a sliding movement, the pitman-rod being connected to a pin or bolt which depends from the under side of the bearing i^2 . Upon the plate or bar i^1 is pivotally connected an arm or lever K , the pin or fulcrum thereof having a suitable spring coiled about the same, the free end thereof engaging with the pin or stud which projects from the lever, the tendency thereof being to throw the lever toward the strip or plate k' , which is provided with a projecting portion with which a dog on the lever engages, so that when the dog and catch are in engagement the sliding frame will be held at the limit of its movement in one direction—that is, toward the opposite end of the machine. In the bearings is mounted a shaft K' , having adjacent to the bearings collars which are rigidly affixed to the shaft and abut against the shaft-bearings, so that said shaft may have a sliding movement with its bearings. The shaft K' is preferably hollow, and one end carries a cap or hood J , and the end of the shaft to which this cap or hood is secured carries a rod j , which is mounted in bearings located within the shaft, and between the bearings is a spring, the function of which is to force the rod j outwardly, said spring bearing upon a collar carried by the rod within the shaft and against the inner guide-bearing, as shown. The rod j within the hollow cap or hood has a stop which is adapted to bear against the outer bearing for the rod when the same is compressed to limit the inward movement thereof, and the outer end may have a pin which is adapted to enter the center of the basket-splints, as will be hereinafter set forth. The cap or hood J is attached to the end of the shaft, so that it can be removed when it is desired, in order that another cap or hood of a different size may be applied thereto.

In order that the splints may be quickly centered and adjusted, I attach to the frame a centering device which consists of a segmental plate J' , which is provided with an upwardly-projecting flange on one edge. This segmental flanged plate may be semicircular and is mounted on the frame so as to be adjustable both vertically and transversely, a preferred means for supporting the same being by means of a standard which depends from the semicircular centering-plate and engages with a cross-bar J^2 , carried by the tie-

rods G, to which it is bolted. The cross-bar is provided centrally with a slot and the centering device is clamped thereto by means of nuts which engage with the standard above and below the supporting-bar. It will thus be noted that the centering device has not only a vertical range of adjustment, but may be adjusted transversely upon its support and longitudinally with respect to the frame by 10 loosening the clamp-bolts which attach the cross-bar thereto.

The standards or steeple-frames E F are constructed to provide bearings for a shaft L, said shaft having loosely mounted thereon a 15 driving-pulley L', which is similar in construction to the pulley H', and it has a clutch with a projecting member with which the slide m engages to cause the shaft to turn with the pulley. Movement of the slide is effected by 20 operating the rock-shaft, which is journaled in the bearings c c', said rock-shaft having a crank-arm which engages with a foot-lever L², said foot-lever or crank-arm being held normally raised by means of a spring which is 25 connected thereto or to the crank-arm and to the tie-rod above. The outer end of the shaft L carries a slotted pitman-wheel L³, and near the other end of the shaft is a sprocket-wheel L⁴.

30 M refers to a shaft which is mounted in bearings attached to the upper ends of the frames E F, said shaft being capable of a rotary movement therein, and one end of this shaft carries a ratchet-wheel M', which is rigidly 35 affixed thereto, and on the shaft adjacent to the ratchet-wheel is a pawl-carrying frame M², which is adapted to oscillate thereon, said frame carrying a dog or pawl which engages with the teeth of the ratchet-wheel. The 40 frame M² is connected by a pitman-rod to the pin which projects from the pitman-wheel L³, the same being provided with the usual wrist-pin and means for adjusting the wrist-pin in the pitman-wheel, the rod also being provided 45 with means for lengthening or shortening the same, so that the rotary movement of the shaft M may be varied as desired. Upon the shaft M, between the supporting-frames, is mounted a pulley N, said pulley engaging the 50 shaft so as to turn loosely thereon, and is adapted to be placed in engagement with the shaft by the movement of a friction-disk N', which is mounted on the shaft so as to rotate therewith. The friction-disk is also connected 55 to a friction-disk N², which when moved in the proper direction engages with the cap N³, carried by the upper end of the standard or frame E.

60 The two disks N' N² are connected to each other, and the connecting portion carries a pin which enters a slot in the shaft, and over the connecting portion is a sleeve with outwardly-projecting pins, which engage with apertures in the spanning portion of a lever 65 N⁴. The lever is fulcrumed upon the frame at a suitable point, preferably upon one of the tie-rods. When the lever N⁴ is thrown to

the left, the disk N' will be moved so as to engage the pulley N to cause a continuous rotation of the shaft M, and when moved to 70 the limits of its movement toward the right will cause the friction-disk N² to engage the cap N³ and hold the shaft against rotation, thus furnishing the shaft with a positive brake. When the friction-disks are positioned so as to be out of engagement with the pulley N and the cap N³, said disks will simply turn with the shaft. The shaft M is also provided with a friction-brake which consists 75 of a pulley N⁵, preferably with side flanges, 80 the pulley being keyed to the shaft, and over this pulley passes a band or strap, one end of which is secured to the frame, the other end carrying a weight. This friction-brake prevents undue rotation of the shaft and holds 85 the same against any backward movement which might be imparted thereto by the return movement of the frame M² and its dog or pawl. The same form of friction-brake is used upon the pulley H⁵ on the shaft H, and 90 it is obvious that any other suitable form of friction-brake may be used. The inner end of the shaft carries a form O, which is fixedly attached to said shaft, and this form has circumferential shoulders o o' and a concave 95 end, the exterior of the form or head tapering or being shaped to correspond generally with the interior configuration of the basket. The end of the shaft M to which the form or head is secured carries a rod o², which is spring-projected, the spring lying within the shaft 100 and bearing upon a cross-piece. This shaft has also collars or nuts, one to prevent the disengagement of the rod and the other to provide a bearing for the spring, the latter 105 being rigidly attached to the rod. The rod in operation is adapted to be forced within the shaft, and when not held therein by pressure exerted thereon the spring is of sufficient strength to force the completed basket off of 110 the form or head.

In the bearings a a', at the rear side of the machine, is journaled a crank-shaft P, the crank portion thereof being preferably on a line with the form O, and one end of this 115 crank-shaft carries a sprocket-wheel P', over which passes a chain which gears said sprocket-wheel to the sprocket-wheel L⁴ on the shaft L. Upon the crank-shaft P, within the bearings a a', is mounted a bifurcated 120 arm or frame Q, the upper end of which has a flat top, to which is attached the base of a stapling-machine. To the lower portion of the bifurcated arm, slightly above the bearings, is attached a foot-lever Q', and to this 125 foot-lever are secured brace-rods q, which extend to the arm and serve as a brace for said foot-lever. The rear end of the foot-lever is bifurcated, so as to span the center portion of the arm Q and clear the crank-shaft. 130 To the upper end of the arm Q is attached the base-plate of a stapling-machine R, the frame of which has bearings for a reciprocating shaft R', which actuates the wire-feed

mechanism, staple, former, and driver, the frame which is connected to the shaft R' carrying said parts of the stapling-machine, the reciprocating movement being imparted to 5 the stapling-machine by the shaft R' , which is connected at its lower end to a pitman R^2 , which is coupled to the vertical reciprocating rod and crank-shaft. The main reciprocating angle-frame R of the stapling-machine is adjustably attached to the rod R' by means of 10 set-screws.

The stapling-machine, as to its individual operating parts, has the usual mechanism for carrying and feeding the wires forming the 15 staples and driving them duplicated and arranged in a novel manner upon an angle-frame, and a particular description as to the construction of these parts is deemed unnecessary.

20 The features of the stapling-machine which adapt it for use with a basket-making machine consist in a duplication and reorganization of the operating parts, wherein I provide a double stapling-machine which makes from coils of 25 wire pointed staples, which will clench when they engage the surface of the form, and by means of which stapling-machine two staples are driven simultaneously by the depression of the rod which carries the reciprocating 30 parts of such device, and in the frame which supports the two stapling-machines, so they will operate in unison, said support also carrying two frames to receive separate coils of wire.

35 The plungers or staple formers and drivers of each stapling-machine are positioned at opposing angles with each other, so that the staples will be driven through the hoops and the splints of the basket at an angle with the 40 length of the hoops and splints, the grain of the wood being on a line with the length of these parts.

A stapling-machine constructed to operate in conjunction with a form to which is imparted an intermittent rotary movement is 45 illustrated by Figs. 12 to 19, inclusive, of the accompanying drawings, and such a machine has its lower or fixed frame bolted to the upper end of the swinging support Q . The lower 50 or base frame S is preferably a casting having apertures in alignment, through which passes the shaft R' , and said frame has forwardly-projecting arms S' , which diverge and carry portions S^2 , which are at opposing angles with 55 each other to provide supporting means for certain parts of the stapling mechanism. The lower forward portion of the main or base frame has formed integral therewith an outwardly-projecting lug or abutment S^3 , with 60 lateral extensions s , upon which are mounted the hoop-rollers $r' r'$, and it will be noted that one of these rollers is of less diameter than the other, the smaller roller being positioned opposite the larger diameter of the form. The 65 lug S^3 has in its upper portion a threaded aperture for the reception of a bolt t , which connects thereto a resilient plate r , carrying a

cross-piece which is provided with upwardly-projecting guide-pins r^3 , which are in a line with the edges or flanges of the hoop-rollers. 70

Between the forwardly-projecting arms or side pieces S' of the base-frame is bolted an angle-plate s^2 , which is bent to provide abutting means for springs s^3 , which engage with reciprocating bars s^4 , over which the wire is 75 bent to form the staples, said bars having projecting studs or pins s^5 , with which bars s^6 , connected to the reciprocating frame R^2 , engage, so as to retract the staple-bar at the proper moment, the lower ends of said bars 80 s^6 being beveled. (See Fig. 18.) The lower ends of the staple-bars s^4 project at right angles with the upper or vertical portions thereof, and said vertical portions are flattened, so as to be resilient. The staple-forming bar 85 T is provided with a longitudinal open-ended slot in its lower portion, having side recesses to guide the lower end of the staple-driver T' and permit the wire entering said recesses when the staple is being formed over the bar 90 s^4 , and the upper portion of the slot is of a greater width than the part below, so as to form shoulders or stops for the driver, and by reference to Fig. 19 it will be seen that one side of the lower end of the staple-forming 95 bar is beveled, which bevel corresponds with the end of a cutting-bar T^2 , which is carried by the frame at right angles with the staple former and driver, the same being on a line with the feed-wheel for the wire, this 100 bar T^2 having its upper face grooved for the passage of the wire, and it is also adjustably connected to the frame, so that it can be removed for sharpening. The bar T , in connection with the bar T^2 , cuts the wire from 105 which the staple is formed at an incline, so that the staple produced will have its ends pointed or beveled, and it will also be noted that as the wire is fed to the staple-forming 110 mechanism by the ratchet feed-wheel and tension-roller through the groove or recess in the upper edge of the cutting-bar the beveled end of the wire will abut against one of the walls of the recess in which the staple forming and driving bars are located and 115 that the staple produced will have one leg thereof longer than the other, it being desirable that only one leg of the staple should be clenched, the other leg being of sufficient 120 length to pass through the hoops and splints 125 of the basket. The upper end of the staple-driving bar T' is attached to the reciprocating frame, and to said frame are also pivoted latches T^3 , which have studs t^3 for engagement with the edges of the face-plates T^4 , the 130 upper portion of said plates having inclined shoulders t^4 , which throw the latches against the action of springs t^5 , also attached to the reciprocating frame. On the downward movement of the upper section of the stapling-machine the latches T^3 engage with the upper end of the bar T and force the same downwardly over the projecting end of the staple-bar s^4 , which cuts the wire, bends it so as to

form the staple, and when this is accomplished the stud t^3 engages the shoulder and is thrown out of engagement with the staple-forming bar, and said staple-forming bar is forced 5 normally downward by a spring t^6 , attached to the reciprocating frame, the free end of said spring engaging a stud or bolt, the head of which may lie over the face-plate. The staple-forming bar is raised against the action 10 of the spring by the portion of the staple-driving bar which lies in the enlarged portion of the slot.

The feed-wire mechanism comprises a tension-roller u , which has a peripheral groove or recess, said roller being mounted on a crank-shaft u' , journaled in bearings, as shown in Fig. 15, the roller being mounted eccentrically with the axis of its supporting-shaft, so that when the shaft is turned the roller u will be 20 moved toward or away from the feed-wheel located above. The inner ends of the shafts u' have attached thereto a lever u^2 , the upper ends of which carry set-screws adapted to abut against angle-blocks carried by the 25 frame, so that by varying the position of the set-screws the distance between the tension-roller and the feed-wheel may be varied. The feed-wheels u^3 have serrated rims u^4 , which enter the groove in the periphery of the tension-roller, and the feed-wheels have ratchet-teeth with which pawls u^5 , which are pivotally attached to the reciprocating frame R^2 , engage, said pawls being thrown toward the ratchet-wheels by suitable springs. The 30 frames above the ratchet-wheels carry recessed plates V , having recesses through which the pawls pass, so that said pawls may have a reciprocating movement with the frame R^2 and are held in alignment with the ratchet-teeth in the feed-wheel. The bolts which 35 carry the feed-wheels also provide supporting means for the arms r^2 , which have openings or perforations through which the wire passes, said wire being carried by projecting arms W , 40 Fig. 2, upon which the wire-reels are placed.

It will be particularly noted that the frames of the stapling-machine are of such shape that the staple-drivers and openings through which the staple-bars pass are at an angle with respect to the longitudinal center of the basket-form, so that when the staples are driven 45 through the hoop and splints they will be positioned diagonally with respect to the length of the hoops and splints, and consequently out of line with the grain of the wood. With a stapling-machine constructed as shown I do not use an anvil, for the surface of the basket-form will turn the beveled ends of the staples and upset them, so as to clinch on the inner 50 side of the basket.

In operation when it is desired to make baskets a form or head and cap of the proper size are attached to the shafts K' M and the different parts of the machine adjusted to suit 55 the sized basket which is to be made. The inner hoops, which may be made by hand or on a separate machine, are placed on the head

or form O , so that they will bear against the shoulders thereof, the upper inner hoop having the handles of the basket attached thereto. 70 The operator takes the splints, which are of proper length, places them in the centering device, holding them there while he depresses the foot-lever H^2 , which moves the slide h' to the left, so as to engage the finger h^7 of the 75 clutch, so as to positively connect the driving-pulley with the shaft H . The pinion h^2 , which meshes with the cog-wheel I on the vertical shaft I^2 , which is connected to the slide, moves the shaft and its journal toward the form or 80 head. Before the shaft reaches the limit of its movement toward the form the splints which are then engaged by the rods are spread, and a further movement of the shaft causes the cap to bend the splints over the form and 85 hold them thereon. When the shaft K' , to which the cap is attached, reaches the limit of its movement toward the form, the dog on the lever K engages the notch in the sliding frame, so as to hold the frame locked against 90 movement away from the form. As soon as the dog engages the sliding frame the operator releases the foot-lever.

If desirable, the slide may be operated by a hand-lever instead of by power; but I prefer power, as considerable force is required to bend the splints into the concave portion and about the form, and the operator needs the use of his hands in setting the splints and adjusting them prior to bending. 100

The bar or rod impinging against the splints and having a limited inward movement forces the splints into the concave portion of the form, while the rod or bar o^2 opposite is forced within the hollow shaft. The next operation 105 is for the operator to depress the foot-lever Q' , which moves the arm or frame Q toward the head or form and positions the stapling-machine directly above the same, said arm or frame having previously occupied a position 110 to one side of the form, so as to provide a space for placing thereon the inner hoops and bending the splints over the head. The operator keeps his foot upon the lever Q' and inserts the outer hoops under the hoop-rollers 115 r' , they being guided by the upwardly-projecting pins or lugs r^3 , which project from a transverse bar r , attached to the front end of a spring-plate, the pins being in front of the side flanges of the rollers r' . The next 120 operation is to depress the lever L^2 , which causes the slide m to engage the finger of the clutch, so as to lock the pulley L' to the shaft, and the rotation of the shaft L through the mechanism before described, which imparts 125 an intermittent rotary movement to the shaft M and its head O in a direction away from the operator, and at each partial rotation the stapling-machine is operated through the intervention of the sprocket-wheels, their chain, 130 crank-shaft, and pitman-rod, so as to cause a reciprocation of the bar R' of the stapling-machine, which imparts a movement to the plungers thereof, feeds the wire from the wire-

holders, and forms it into staples, the plunger driving the staples through the outer hoops, the splints, and through or into the inner loops.

- 5 Should it be desirable at any time to revolve the form or head independent of the stapler, this can be accomplished by throwing the lever N^4 to one side, so that the friction-disk will engage with the driving-pulley N , and after revolving the shaft by said means it may be brought to an immediate stop by an opposite movement of the lever.

The styles of baskets which this machine is designed to manufacture are the ordinary bushel-baskets and half-bushel baskets, which are made up of splints and have inner and outer hoops and handles, which are attached to the inner hoop. Other styles of baskets may be made, as well as berry-boxes, either 20 of round or octagonal form.

Having thus described my invention, I do not wish to be limited to the precise construction of the parts herein shown and described nor to the manner of driving, as the different 25 shafts may be geared to each other, or a different arrangement of pulleys may be provided, without departing from the spirit and scope of my invention.

In a basket-making machine of the character described the driving-shaft L is connected with the shaft M , upon which the basket-form is mounted, so that an intermittent rotary motion will be given to the form, and said driving-shaft is also geared to the crank-shaft P , which in turn is connected with the stapling-machine, so that on the downstroke of the rod R' of the stapling-machine the staples will be driven, such driving of the staples being between the impulses given to the form by the 40 pawl and ratchet, or, in other words, the staples are driven while the pawl is making its back movement.

In placing the inner hoops upon the form the driving-shaft L is out of gear with the driving-pulley L' and the shaft carrying the form is given a continuous rotary motion by means of the driving-belt, which passes over the pulley N , and during this continuous rotary movement of the form the stapling mechanism is idle, though it may be moved forward to its extreme limit, so that the hoop-guides and hoop-rollers carried by the lower frame may be utilized in bending the inner hoops about the form.

55 The style of basket which is made by this machine is made up of splints or strips, which not only form the bottom of the basket, but also the sides.

Having thus described my invention, what 60 I claim as new, and desire to secure by Letters Patent, is—

1. In a basket-making machine, the combination with a form mounted on a shaft connected with mechanism for imparting an intermittent rotary movement or a continuous rotary movement thereto, a shaft journaled in line therewith and provided with a hood

or cap, means for moving the same over the form so as to bend and retain the basket-splints thereon, of a stapling-machine mounted on a swinging support so that it can be moved into operative position over the form or to one side of the same, when placing the splints on the form or removing the completed basket therefrom. 70

2. In a basket-making machine, a shaft having a basket-form carried thereby, a cap or hood carried by a shaft on a line therewith, said shaft being mounted so as to be moved to and from the form, a stapling-machine 80 mounted on a swinging support, the driving-shaft of the stapling-machine being in gear with the driving mechanism for the shaft upon which the form is mounted, said mechanism embodying a pawl and ratchet for imparting 85 an intermittent rotary motion to the form and gearing to operate the stapling-machine when the form is at rest, substantially as shown and for the purpose set forth. 75

3. In a basket-making machine, the combination with a shaft having a basket-form attached thereto, mechanism for imparting to said shaft and basket-form an intermittent rotary motion, a pulley mounted on the shaft so as to impart when it positively engages the 90 shaft a continuous rotary movement, a second shaft mounted on a line with the shaft carrying the form, the same being provided with a hood or cap, and means for supporting the shaft so that it may be moved to place the 95 hood or cap partially over the form; together with a stapling-machine supported so as to be moved to an operative position over the form or to one side of the same, the stapling-machine being connected with the shaft carrying 100 the form so that a downward movement of the staple-drivers will be effected when the form is at rest, substantially as set forth. 105

4. In a basket-machine, the combination of a horizontally-mounted shaft carrying a basket-form, of a shaft mounted on a line therewith and provided with a cap or hood for bending the basket-splints over the form, said shaft being connected with means for moving the same longitudinally, the basket-form having 115 its end adjacent to the hood or cap concave, and a spring-projected rod carried by the shaft upon which the hood or cap is mounted for bending the splints in the concave portion of the basket-form, for the purpose set 120 forth. 110

5. In a basket-making machine, the combination with the shafts one carrying a form having a concave end and the other a cap or hood, the shaft carrying the cap or hood being movable longitudinally to and from the form, of spring-projected rods carried by the shafts so as to be on a line with each other to provide means for holding the splints and forcing them in the concave portion of the 130 basket-form prior to the engagement of the hood or cap with said splints, said hood or cap bending and holding the splints over the form while the bands are being applied thereto, 125

the spring-projected rod carried by the shaft upon which the form is mounted projecting the basket from the form when the cap is moved away therefrom, for the purpose set forth.

5 6. In a basket-making machine the combination with shafts one having a form with concave end and the other a splint-bending cap mounted thereon, of spring-projected rods carried by the shafts and positioned centrally with respect to the form and cap, one of the rods having means for limiting its inward movement so that a part thereof will be positively projected to force the splints into the concave end of the basket-form prior to 15 the bending of the splints over the form by the cap, for the purpose set forth.

7. In a basket-making machine the combination with a basket-form mounted on a horizontal shaft, said form having shoulders to provide inner hoop-bearings, the outer end of the form being concave, a hood or cap mounted on a shaft having means for moving the shaft so as to position the hood or cap over the form, the shafts upon which the form and hood or cap are mounted each carrying spring-projected rods which hold the splints centered, one of the rods having means for holding the same positively projected so as to 25 bend the splints within the concave portion of the form, the hood or cap subsequently bending the splints over the form, substantially as shown and for the purpose set forth.

8. In a basket-machine, the combination 30 with a form having a concave end, of a hood or cap adapted to bend the splints over the form, a rod carried by the shaft upon which the hood is mounted, a spring for projecting said rod and a collar or stop to limit the inward movement of the rod to provide a projecting portion which will force the splints into the concave portion of the form.

9. In a basket-making machine, the combination of a shaft mounted so as to be rotatable in bearings, the bearings being supported so as to have a longitudinal movement, a hood or cap for the purpose set forth mounted on one end of the shaft, a lever fulcrumed on a fixed frame and provided with a projecting portion for engagement with the sliding frame having the bearings and means substantially as shown for effecting the movement of the sliding frame for the purpose set forth.

55 10. In a basket-making machine, the combination with a form, of a cap or hood mounted on a shaft, means for moving the shaft and hood to and from the form embodying a sliding frame with bearings in which the shaft is journaled, a pitman connected to the sliding frame and to an arm or disk, a vertical shaft on which said arm or disk is mounted, a gear-wheel on the lower end of said shaft; together with a horizontal shaft having a 60 driving-pulley loosely mounted thereon, a sliding block for throwing a clutch of the driving-pulley in engagement with the shaft

and a lever for moving said clutch, substantially as shown.

11. In a basket-making machine, the combination with a form and hood having spring-projected splint-holding bars or rods, of a centering device positioned beneath the form and cap so as to occupy an intermediate position between the same with which the ends 75 of the splints are adapted to engage, substantially as shown.

12. In a basket-making machine having a form and hood, of a segmental plate supported beneath the same to serve as a centering device for the splints, together with spring-projected splint-holding bars carried by the shafts upon which the form and hood are mounted so as to engage with the center 80 of the splints, substantially as shown.

85 13. In a basket-making machine having a form and hood or cap, of a segmental centering device supported beneath the same said centering device having on one of its edges an upwardly-projecting flange, the supports 90 for the form and hood having spring-actuated splint-holding rods beneath which the centering device is positioned for the purpose set forth.

95 14. In a basket-making machine, the combination with the shafts having hollow ends upon which are mounted a form and hood for bending the splints over the same, spring-actuated splint-engaging rods carried by the hollow shafts; together with a segmental centering device adjustably mounted upon the frame below the splint-holding rods for the purpose set forth.

100 15. In a basket-making machine, the combination with a form and means for holding 105 splints thereon and imparting a rotary movement thereto, of a stapling-machine mounted on a swinging support so as to be moved into operative position over the form, said stapling-machine having a pair of staple-drivers 110 maintained at opposing angles with each other and with the grain of the hoops and splints.

115 16. In a basket-making machine, the combination with a stapling-machine mounted on a movable support the same having in front 115 of the staple-drivers thereof hoop-rollers, of a form mounted on a shaft said form having shoulders against which the inner hoops of the basket abut positioned so that the inner hoops will be beneath the staple-drivers and 120 hoop-rollers adjacent thereto when the stapling-machine is moved over the form, for the purpose set forth.

125 17. In a basket-making machine, the combination with a form and a cap for holding 125 the splints thereon, and means for imparting an intermittent rotary movement to the form, of a stapling-machine having a pair of rollers for the exterior hoops and mechanism for driving two staples simultaneously when the 130 form is at rest, the shaft carrying the form and the driving-shaft of the stapling-machine being in gear with each other, substantially as shown and for the purpose set forth.

18. In a basket-making machine, the combination with a shaft having means for imparting an intermittent rotary movement thereto, a form mounted on said shaft, a stapling machine supported so as to be moved to one side of the form to provide room to bend the splints upon the form, the stapling-machine being moved over the same when in operative position, a cap or hood for holding the splints on the form and mechanism substantially as shown for operating the stapling machine when the form is at rest for the purpose set forth.

19. In combination with a basket-making machine having a form and means for holding the basket-splints thereon, of a stapling-machine mounted on a swinging support, a foot lever or brake for moving the stapling-machine above the form; together with means for throwing the driving mechanism which operates the stapling-machine in gear with the shaft upon which the form is mounted, substantially as shown.

20. In a machine for making baskets from splints and hoops, a form over which the splints are bent, a cap for bending and holding the splints thereon, in combination with a stapling-machine which is movable at right angles to the longitudinal axis of the form, rollers carried by the frame of the stapling-machine in advance of the staple-driving mechanism and a cross-bar having upwardly-projecting guide-pins, supported so as to be positioned in advance of the rollers, substantially as shown and for the purpose set forth.

21. In a basket-making machine, the combination with a form and a cap or hood for holding the splints thereon, the shaft upon which the form is mounted carrying a ratchet-wheel, means for turning the ratchet-wheel, said shaft also carrying a friction-brake to provide means for holding the shaft against rotation; together with a stapling-machine and means for operating it from the driving-shaft to which the shaft carrying the form is geared so that the staples will be driven when the form is at rest for the purpose set forth.

22. In a basket-making machine, the combination of a pair of shafts in alignment with each other, one of the shafts having a basket-form mounted thereon, the other shaft carrying a cap or hood for bending and holding the splints upon the form, means for imparting an intermittent rotary movement to the shaft carrying the form, a stapling-machine in gear with a main driving-shaft, said main driving-shaft also being connected to the shaft carrying the form, means for disengaging the driving-pulley from the main driving-shaft, a pulley mounted on the shaft carrying the form and a clutch adapted to be placed in engagement therewith, so as to effect a continuous rotary movement of the form without operating the staple-driving mechanism, the parts being organized and combined substantially as shown and for the purpose set forth.

23. In a basket-making machine, the combination of an intermittently-driven shaft carrying a form, of a shaft mounted so as to be movable to and from the form, a hood carried by said shaft, driving-shafts as H, L, and means for connecting said shafts with the shafts carrying the form and hood, pulleys loosely mounted on the shafts L, H, and foot-levers having their ends projecting toward each other, said foot-levers being connected to rock-shafts having arms for engagement with slides mounted on the shafts L, H, so that when the foot-levers are depressed the slides will be moved to engage clutches on the shafts so that said pulleys will be positively connected with the shafts; together with an arm pivotally attached to a crank-shaft, said arm carrying stapling mechanism, a foot-lever for bringing the arm forward so that the stapling mechanism will be in operative position and gearing for connecting the crank-shaft to the shaft L, the parts being combined and organized substantially as shown and for the purpose set forth.

24. In a basket-making machine the combination with the form and means for holding splints thereon and imparting an intermittent rotary motion to the form and splint-holder, of a duplex stapling-machine having separate plungers and staple-forming devices, guide-rollers and wire-holders, motion being imparted to the operative parts by a single rod which is reciprocated from the shaft which drives the shaft carrying the form, the stapling-machine also carrying in front of the staple-inserting plungers, flanged rollers for the hoops and an intermediate resilient bar carrying a cross-bar with upwardly-projecting pins, the parts being organized substantially as shown and for the purpose set forth.

25. In a basket-making machine, the combination with a form, and a hood or cap for bending the splints and holding them on the form, the form and the hood or cap being mounted on independent shafts, means for moving longitudinally one of the shafts so that it will turn in unison with the shaft carrying the form, of a stapling-machine carried by a swinging support, so as to be positioned away from the form and brought over the form, the basket-form serving as an anvil for the staple-drivers, substantially as set forth.

26. The combination in a basket-making machine, having a driven shaft to which is imparted an intermittent rotary movement, a basket-form carried by said shaft and a cap or hood for holding the basket-splints thereon, of a stapling-machine mounted on a swinging support, the driving-shaft of the stapling-machine being geared and ordinarily arranged to operate the staple-drivers which are indirectly connected with said shaft so that the downward movement thereof will be between the impulses of the basket-form, the mechanism embodying a driving-shaft with which the driving-shaft of the form and the

driving-shaft of the stapling-machine are geared for the purpose set forth.

27. In combination with the basket-making machine, a staple making and driving mechanism, comprising a base-frame with stapling mechanism arranged at opposing angles with respect to the longitudinal axis of the basket-form, the base-frame having a centrally-projecting lug upon which are mounted hoop-rollers, a plate carried by the lug so as to project in advance of the hoop-rollers, said plate having upward-projecting pins; together with a reciprocating frame the downward movement of which actuates the mechanism which forms and drives the staples, substantially as shown.

28. In combination with a basket-making machine, a stapling-machine having a pivotally-supported base-frame with staple making and driving mechanisms carried thereby so as to be at opposing angles relative to the longitudinal axis of the basket-form, an operating-rod which passes through and is guided by the base-frame, a frame mounted on said shaft so as to reciprocate therewith said frame carrying depending members which actuate

the staple making and driving mechanisms and means in engagement with each other for rotating the basket-form and reciprocating the operating-rod of the stapling mechanism, substantially as shown and for the purpose set forth.

29. In combination with a basket-making machine, a duplex stapling-machine comprising a lower base-frame, the portions which carry the staple making and driving mechanisms being arranged at opposing angles with each other, a driving-rod for operating both staple making and driving mechanism, said rod passing through the base-frame and being guided thereby, a reciprocating frame carrying pawls for operating the feed-wheels, latches for engagement with the staple-formers, and staple-drivers connected to the upper reciprocating frame, substantially as shown and for the purpose set forth.

In testimony whereof I affix my signature in presence of two witnesses.

ROGER E. REED.
